CLAIM

The ornamental design for a compartmented carton insert, as shown and described.

DESCRIPTION

FIG. 1 is a perspective view of a compartmented carton insert showing a new design; and,

FIG. 2 is a perspective view of the compartmented carton insert showing an alternate configuration.

The dash-dash broken lines are for the purpose of illustrating environment and form no part of the claimed design.

1 Claim, 2 Drawing Sheets# US D875,530 S
